United States Patent Office

Des. 227,385

Patented June 19, 1973

227,385

TOY DRAGSTER

Larry R. Wood, Lawndale, Calif., assignor to
Mattel, Inc., Hawthorne, Calif.

Filed Oct. 4, 1971, Ser. No. 186,598

Term of patent 14 years

Int. Cl. D21—01

U.S. Cl. D34—15 AJ

FIG. 1 is a perspective view of the toy dragster showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a right side elevational view thereof; and

FIG. 7 is a bottom plan view.

I claim:

The ornamental design for a toy dragster, as shown.
